UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A COAT.

Application filed September 1, 1926. Serial No. 18,926. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein the coat is distinguished by having a fur collar arranged with one end extending down to near the bottom of the coat, simulating a scarf by reason of its position and shape, both when the coat is closed and when

open. The coat is also distinguished by the arrangement of ornamental strips on the rear of the sleeves and back of the coat.

Figure 1 is a front view of a coat shown open and showing my new design.

Figure 2 is a view similar to Figure 1 but with the coat shown closed.

Figure 3 is a three-fourths rear view of the coat shown in Figure 1.

I claim:

The ornamental design for a coat, substantially as shown and described.

TAUBE DAVIS.
